LOOSE-LEAF BINDER.

1,375,667.

Specification of Letters Patent. Patented Apr. 26, 1921.

Application filed July 5, 1918. Serial No. 243,276.

To all whom it may concern:

Be it known that we, GOTTFRIED P. BAUMANN and RALPH A. FINK, citizens of the United States, residing at Chicago and Oak Park, respectively, in the county of Cook and State of Illinois, have invented a certain new and useful Improvement in Loose-Leaf Binders, of which the following is a full, clear, concise, and exact description, reference being had to the accompanying drawings, forming a part of this specification.

Our invention relates to loose leaf binders, an object being to provide a simple and improved device of this character in which the loose leaves or sheets are securely held and may be readily removed by a simple manipulation of the locking device. One of the features of our invention is the provision of a hinge-shaft manipulated locking dog for maintaining the binder normally closed.

Our invention is illustrated in the accompanying drawing in which—

Figure 1 is an edge view of the binder in closed position and with some sheets in place;

Fig. 2 is a view looking at the inside of the binder and with the binding mechanism closed but the cover open;

Fig. 3 is a view similar to Fig. 2 but with the binding mechanism opened;

Fig. 4 is a longitudinal section through the hinge along the line 4, 4 of Fig. 2;

Fig. 5 is an edge view of the binder with its cover open as in Fig. 2;

Fig. 6 is an edge view of the binder as shown in Fig. 3; and

Fig. 7 is a perspective view of the hinge shaft and locking dog.

Referring now more in general to the preferred form of our invention as shown in the accompanying drawing, it consists of the usual cover, and hinged binder mechanism supplied with prongs or studs which enter the holes in the sheets, the binder mechanism being locked by means of a locking dog carried upon the shaft of the binder hinge.

More particularly our invention comprises a cover 1 having a flexible back or connecting portion 2, which may be of any usual and well-known construction.

A binder mechanism is secured to the cover 1 and consists preferably of a hinged member including the two portions 3 and 4 which are suitably secured to the binder

cover preferably by rivets 5. These hinge portions 3, 4 are connected together preferably by means of a shaft 6, which extends 60 through the curled portions 7 of the members 3, 4 so that the hinge may be readily opened and closed by rotating about the shaft 6.

A suitable number of paper engaging elements are provided, these being preferably in the form of tapered studs 8 which are rigidly secured to the hinge and suitably curved so that they will readily enter and leave the punched holes in the sheets which 70 are bound.

It is to be understood that although we have shown four such studs 8, two entering the sheets from each side, the number of such holding studs may be varied as desired 75 and in accordance with the size of the binder. The larger binders would, no doubt, require more studs than the smaller binders.

In order to lock the binder in its closed position we preferably provide locking 80 means in the form of a double dog 9 which is rigidly attached to the hinge shaft 6 and carries locking elements preferably in the form of two extensions 9¹ and 9² which are adapted to engage the outer face of the 85 hinge parts 3 and 4 as shown in Fig. 5, and by the dotted lines in Fig. 2. It will be apparent that with the dog securely attached to the shaft and with its extensions 9¹ and 9² under the opposite parts 3 and 4 90 of the hinge, the hinge is held locked in its closed position. In order to maintain the dog normally in its locking position we preferably provide a spring 10 which encircles the shaft 6 and is compressed between an 95 edge 11 of the hinge and the dog 9 so that the spring normally presses the dog into locking position as shown in Fig. 2.

Now in order to manipulate the locking dog 9 so as to permit opening the binder 100 mechanism, we provide a small unlocking device in the form of a knurled nut 12 which is rigidly secured to the shaft 6. By pressing upon the outer face of the nut 12 when in the normal locking position as indicated 105 in Fig. 2, the shaft 6 and locking dog 9 are moved longitudinally until the locking arms 9¹ and 9² are clear of the edges 13 and 14 of the hinge members as shown in Fig. 3, at which time the hinge may be opened to 110 its sheet removing position as indicated in Figs. 3 and 6.

As soon as the opening movement of the hinge is started and when the dog arm 9²

has rotated past the edge 14 of the hinge, pressure of the finger upon the nut 12 is removed allowing the arm 9² to rest against the edge 13. But having passed out of its 5 normal locking position a continued opening movement of the hinge is permitted.

Now in order to prevent such rotation of the shaft 6 as might throw the dog 9 out of its proper alinement, we preferably provide 10 a slot 12¹ in the nut 12 which slot rides over the edge 3¹ of the hinge portion 3. This slot permits a longitudinal movement of the shaft 6 but prevents any undue relative rotary movement of the hinge and shaft 15 so that the dog 9 is always maintained in its proper relation to the hinge.

In order to close the hinge from its open position as shown in Fig. 6, it is only necessary to grasp the cover of the binder, or 20 manipulate the hinge so as to rotate it about the shaft until it reaches the closed position of the binder at which time the dog is automatically pressed into its locking position by the action of the spring 10.

20 Thus it will be seen that we have provided a simple and inexpensive loose leaf binder in which we preferably employ the shaft of the binder hinge for carrying the locking element and through which the locking element 30 may be manipulated. Furthermore all of the parts are rigidly supported so that there is no undue play and therefore the parts will always properly register.

Although we have chosen a preferred 35 form for the purpose of illustrating our invention, it will be apparent that many changes and modifications will readily occur to those skilled in the art and therefore we do not desire to be limited to the exact structure as shown and described but aim to cover all that which comes within the spirit and scope of the appended claims.

We claim—

1. A loose leaf binder comprising a hinged 45 back, including a shaft for the hinge, and a spring pressed locking dog carried by the shaft for automatically locking the hinge when the binder is closed.

50 2. A loose leaf binder comprising a hinged back, including a shaft for the hinge, a spring pressed locking dog on said shaft for automatically locking the hinge when the binder is closed, and means for manipulating the shaft to unlock the dog.

55 3. A loose leaf binder comprising a hinged back, including a shaft for the hinge, a locking dog carried by the shaft, means for manipulating the shaft to unlock the dog whereby the binder may be opened, and means for automatically moving the shaft and dog into locking engagement when the binder is closed.

4. A loose leaf binder comprising a hinged 65 back, including a shaft for the hinge, a locking dog carried by the shaft, means for

manipulating the dog to unlock the hinge whereby the binder may be opened, and means for automatically moving the dog into locking engagement when the binder is closed.

5. A loose leaf binder comprising a hinged 70 back, including a shaft for the hinge, and a locking dog carried by the shaft for engaging the back sides of the opposing hinge portions to lock the hinge.

6. A loose leaf binder comprising a hinged 75 back, including a shaft for the hinge, a locking dog carried by the shaft, means for manipulating the dog to unlock the hinge whereby the binder may be opened, means 80 for automatically moving the dog into locking engagement when the binder is closed, and rigid studs carried upon opposed sides of the hinge and adapted to enter the sheets from opposite sides.

85 7. A loose leaf binder comprising a cover, a two piece hinge having opposed sides secured to the cover, and including a longitudinally movable shaft for the hinge, a locking dog carried by the shaft for engagement with the back faces of opposed sides of the hinge, and means whereby the shaft may be moved longitudinally to disengage the dog from the hinge whereby the hinge may be opened.

90 8. A loose leaf binder comprising a cover, a two piece hinge having opposed sides secured to the cover, and including a longitudinally movable shaft for the hinge, a locking dog carried by the shaft for engagement with the hinge, means whereby the shaft may be moved longitudinally to disengage the dog from the hinge whereby the hinge may be opened, and means for automatically effecting a locking engagement of 100 the dog and hinge when the hinge is closed.

95 9. A hinge for loose leaf binders comprising the two attaching parts, a locking dog movable longitudinally of the hinge axis and having an arm adapted to engage one of the parts to hold the hinge closed, means to prevent rotation of the dog while the hinge is closed, and means for moving the dog longitudinally to an unlocked position.

110 10. A loose leaf binder comprising a hinged back, including a shaft for the hinge, and a locking dog carried by the shaft for engaging the back side of a hinge portion to lock the hinge.

115 11. A loose leaf binder comprising a hinged back, including a shaft for the hinge, and a locking dog mounted on said shaft and engaging the back side of the hinge to lock the same.

120 In witness whereof, we hereunto subscribe our names this 19th day of June, A. D., 1918.

GOTTFRIED P. BAUMANN.
